US00D930700S

(12) **United States Design Patent** (10) Patent No.: **US D930,700 S**
(45) Date of Patent: **** Sep. 14, 2021**

(54) **DISPLAY SCREEN WITH GRAPHICAL USER INTERFACE**

(71) Applicant: **Google LLC**, Mountain View, CA (US)
(72) Inventors: **Sung Min Kim Arena**, San Francisco, CA (US); **Nayon Kim**, Sunnyvale, CA (US); **Jessica Suen**, Sunnyvale, CA (US); **J. Christopher Irwin**, Palo Alto, CA (US); **Andrew Schoneweis**, Sunnyvale, CA (US)

(73) Assignee: **GOOGLE LLC**, Mountain View, CA (US)

(**) Term: **15 Years**

(21) Appl. No.: **29/769,551**

(22) Filed: **Feb. 5, 2021**

Related U.S. Application Data

(62) Division of application No. 29/693,428, filed on Jun. 3, 2019, now Pat. No. Des. 916,903.

(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with user interface showing a first embodiment according to the claimed design; and,

FIG. 2 is a front view of a display screen with graphical user interface showing a second embodiment according to claimed design.

The broken lines illustrate the display screen and a boundary and form no part of the claimed design.

**1 Claim, 2 Drawing Sheets
(2 of 2 Drawing Sheet(s) Filed in Color)**
